HEAT EXCHANGE UNIT

Walter H. Geddes, Dayton, Ohio, assignor to
 United Aircraft Products, Inc., Dayton, Ohio, a
 corporation of Ohio

Application April 7, 1943, Serial No. 482,153

4 Claims. (Cl. 257—2)

1

This invention relates to heat exchange units, especially for cooling hot, viscous liquids such, for example, as the lubricating oil of internal combustion engines, and has for particular reference to improvements in heat exchange units of the type comprising, generally speaking, a heat exchange portion in the form of a core which is surrounded by a passageway through which the liquid to be cooled flows prior to entering the core and through which the liquid may flow in by-passing relationship to the core, in the event the latter may become obstructed to flow of the liquid therethrough due to congelation of the liquid therein or to any other cause.

One well known form of heat exchange unit of the type referred to and with which the present invention is concerned, comprises a casing enclosing the heat exchange core portion of the unit, and a jacket surrounding said casing and providing a passageway extending therearound. The jacket is provided at a suitable point, at the top thereof, for example, with an opening for the inlet to said passageway of the liquid to be cooled, and the casing is provided at a point diametrically opposite or substantially diametrically opposite said inlet opening, at the bottom thereof, for example, with an inlet opening for flow of liquid into the casing from said passageway. In addition, the casing is provided at a point diametrically opposite or substantially diametrically opposite its inlet opening, at the top thereof, for example, with an outlet opening for flow of the liquid therefrom, and the jacket is provided at a suitable point, at the top thereof, for example, with an opening, for outlet of the liquid from said passageway. Normally, however, the jacket outlet opening is closed by a valve so that the liquid is prevented from flowing in by-passing relationship to the core portion of the unit and is required to flow through said core portion. Said valve is, however, maintained normally closed by suitable yieldable means so that it may open under a higher-than-normal pressure in the system of which the unit is a part. Accordingly, if the core portion of the unit should, for any reason, become obstructed to flow of the liquid therethrough as, for example, due to congelation of the liquid therein, the pressure in the system will rise until said yieldably closed valve is forced open, whereupon the liquid will flow in by-passing relationship to said core portion until the congealed liquid therein has become de-congealed or such other cause of obstruction to flow therethrough as may exist has been removed. The valve then

2

will close and flow of the liquid through the core portion of the unit will be resumed.

When that portion of the liquid in the system which is contained in the core portion of the unit is cold and congealed and the remaining, hot portion of the liquid in the system is flowing in by-passing relationship to said core portion through the passageway surrounding said core portion, it acts to warm and de-congeal the liquid in said core portion, the de-congealing process being progressively inwardly toward the center of the core portion of the unit.

The initial part of the de-congealing process results in opening of the outer or peripheral part 15 of the core portion of the unit to flow of the liquid therethrough, and when this condition is established flow of the liquid in by-passing relationship to said core portion ceases and is resumed through the said outer or peripheral part of said 20 core portion. However, until all of the congealed liquid in the core portion of the unit has been de-congealed and flow of the liquid through all parts of said core portion has been resumed, the unit does not operate at maximum efficiency to 25 maintain the liquid within a desired temperature range and condition of viscosity best suiting it to perform its engine lubricating or other function. On the contrary, as long as the liquid is circulating in by-passing relation to the core 30 portion of the unit, or through only the outer or peripheral part of the core portion of the unit, it remains too hot.

In heat exchange units of the type under consideration it is usual to provide open-ended tubes 35 extending through the core portions of the units for the flow therethrough of air to cool the liquid flowing through the core portions. It is also usual to provide shutters to regulate flow of air through the tubes and to provide means whereby 40 said shutters are actuated in response to variations in the temperature of the liquid flowing through the core portions of the units. In other words, during normal operation of the heat exchange unit, the shutters are opened and closed 45 with rise and fall, respectively, of the temperature of the liquid above or below a predetermined value so that the liquid is maintained within a desired temperature range.

Heretofore, however, the shutters have controlled flow of air through the tubes at the outer or peripheral parts of the core portions of the units as well as through the more inwardly disposed tubes, and have prevented flow of cooling air through the tubes at the outer or peripheral 55 parts of the core portions of the units until such

times as flow of the liquid through said parts of said core portions has been resumed following periods when the liquid in the core portions has become congealed. During these times the liquid ordinarily is intensely hot and it is extremely desirable that it should be cooled.

Accordingly the object of the present invention is to provide a heat exchange unit of the type under consideration embodying a construction whereby the shutters thereof regulate flow of cooling air through only the more inwardly disposed tubes of the core portion of the unit and do not at any time obstruct flow of cooling air through the tubes at the outer or peripheral part of said core portion, and whereby cooling air is permitted at all times to flow through the tubes at the outer or peripheral part of said core portion, thus to insure at least some cooling of the intensely hot liquid flowing around said core portion in by-passing relationship thereto during times just prior to resumption of its flow through said core portion following any given period when the liquid in said core portion may have become congealed.

With the foregoing and other objects in view, which will become more fully apparent as the nature of the invention is better understood, the same consists in a heat exchange unit embodying the novel features of construction, combination and arrangement of parts as will be hereinafter more fully described, illustrated in the accompanying drawing and defined in the appended claims.

In the accompanying drawing, wherein like characters of reference denote corresponding parts in the separate views:

Fig. 1 is an end elevation of a heat exchange unit embodying the features of the invention, and

Fig. 2 is a side elevation, partly in section, of the unit shown in Fig. 1.

Referring to the drawing in detail, 10 designates a casing which contains the heat exchange core portion of the present heat exchange unit, and 11 designates a jacket surrounding said casing and, in conjunction therewith, providing a passageway *a* extending around the outside thereof.

The jacket 11 is provided at a suitable point, at the top and adjacent to one end thereof, for example, with an opening 12 for inlet of the liquid to be cooled to the passageway *a*, while the casing 10, at a diametrically opposite point, at the bottom thereof, for example, is provided with an opening 13 for inlet of the liquid to said casing from the passageway *a*. In addition, the casing 10 is provided at a point diametrically opposite or substantially diametrically opposite the opening 13, at the top thereof, for example, with an opening 14 for outlet of the cooled liquid from said casing, and the jacket 11 is provided at a suitable point, at the top thereof, for example, with an opening 15 for outlet of the liquid from the passageway *a*.

Mounted upon the jacket 11 in covering relationship to the outlet openings 14 and 15 is a housing 16 in the bottom wall of which are openings 17 and 18 which are aligned with the openings 14 and 15, respectively, whereby the liquid may flow into said housing either from the casing 10 or from the passageway *a*. The opening 18 normally is closed, however, by a valve 19 so that the liquid cannot flow from the opening 12 through the passageway *a* and the openings 15 and 18 into the housing 16 in by-passing relationship to the heat exchange core portion of the unit contained

in the casing 10, but in its flow to said housing is required to pass through said heat exchange core portion. The housing 16 has an opening 20 for outlet of the liquid therefrom regardless of whether the liquid enters said housing through the openings 14, 17 or 15, 18.

As is understood, the present heat exchange unit is to be used in a closed-circuit liquid circulating system such, for example, as the lubricant 10 circulating system of an internal combustion engine employing a pump, or pumps, for circulating the liquid under pressure in the system, and in this connection it will further be understood that a delivery conduit from the engine is connected to the inlet opening 12 and that a return conduit to the engine is connected to the outlet opening 20 of the housing 16. Return conduit may or may not include a storage tank, air separator or settling tank.

The valve 19 is closed by suitable yieldable means which exerts a closing force thereon not materially greater than the opening force which is exerted thereon by the pressure of the liquid in the system during normal operation of the system. Thus, while said valve normally is closed and requires the liquid to circulate through the core portion of the unit, it may open and permit circulation of the liquid in by-passing relationship to the core portion of the unit whenever the pressure of the liquid rises above normal. For example, a sudden acceleration of the speed of the engine may produce a pressure of the liquid sufficiently high to open said valve, or in the event the liquid in the core portion of the unit should become congealed and thereby obstruct flow through said core portion, the pressure of the liquid obviously will rise until said valve opens.

In accordance with known practice the casing 10 has extending longitudinally therethrough numerous open-ended tubes 21 through which air may flow to cool the liquid circulated through said casing between said tubes. Also in accordance with known practice, spaced apart partitions 22 are provided in the casing 10 for cooperation therewith and with each other to require the liquid to flow in a tortuous path through said casing so as to be subjected most thoroughly to the cooling effect of the air flowing through the tubes 21.

Further in accordance with known practice, generally speaking, an open-ended casing 23 is mounted upon one end of the casing 10 and projects therebeyond and has pivotally mounted therein a plurality of shutters 24 to be opened and closed to regulate flow of cooling air through the tubes 21.

Additionally in accordance with known practice, a thermal power element 25 is mounted in an opening in the housing 16 and has its inner end portion exposed within said housing at a location where it will be affected by the temperature of the liquid when the liquid is circulating through the core portion of the unit and is entering said housing via the openings 14, 17.

In the housing 16, between the openings 17 and 18, is a partition 26 having therein an opening 27 controlled by a check valve 28 to permit the liquid to flow from the opening 17 to the housing outlet opening 20, but to prevent the liquid, when it is flowing through the openings 15, 18 and the housing 16 to said housing outlet opening 20, from affecting the thermal element 25.

The thermal element 25 may be of any suitable construction such that a part thereof moves in response to changes in the temperature of the

liquid flowing over the inner end portion of said element, and the said movable part of said element is connected in any suitable manner with the shutters 24 whereby the latter are opened in harmony with rise in the temperature of the liquid to permit more cooling air to flow through the tubes 21 and are closed in harmony with lowering of the temperature of the liquid to reduce the amount of cooling air which may flow through said tubes.

In the drawing the aforesaid movable part of the thermal element 25 is indicated by way of example as comprising a reciprocable stem 29 projecting from the outer end of said element, and the connection between said movable part and the shutters 24 is indicated by way of example as comprising lever arms 30 and 31 connected to the stem 29 and to the shaft of one of the shutters, respectively, and connected together by a rod 32, the shutters being connected together by links 33 so that they are opened and closed in unison.

As aforesaid, the prior practice has been to employ shutters which regulate flow of air through all parts of the core portions of units of the type illustrated and described, with the disadvantage mentioned. As distinguished from this prior practice and according to the present invention, the shutters 24 control flow of cooling air only through such of the tubes 21 as are disposed inwardly of the outer or peripheral part of the core portion of the unit and provision is made for flow of cooling air at all times through the tubes 21 at the outer or peripheral part of the core portion of the unit. In this connection and according to the specific construction illustrated in the drawing, the shutter casing 23 includes a larger diameter inner end portion 23^a of approximately the same diameter as the casing 10 to fit over or into the end of the latter casing, and an outer end portion 23^b of materially lesser diameter which contains the shutters 24 and through all portions of which flow of air is controlled by said shutters. The two portions 23^a, 23^b of said shutter casing are joined together by a wall 34 and in this wall is an annular row of openings 35 which are alined, or approximately alined, longitudinally of the unit, with the tubes 21 at the outer or peripheral part of the core portion of the unit. Thus, some cooling air may flow through the tubes 21 at the outer or peripheral part of the core portion of the unit regardless of whether the liquid is flowing through or in by-passing relationship to said core portion and regardless of whether the shutters 24 are open or closed.

Normally the valve 19 is closed and the hot liquid flows, as indicated by the dash and dot line in Fig. 2, from the inlet opening 12 into the passageway a, through said passageway to the opening 13, into the casing 10, tortuously through said casing wherein it is cooled by air flowing through the tubes 21, from said casing through the openings 14 and 17 into the housing 16 and over the inner end of the thermal element whereby its heat causes said thermal element to actuate the shutters 24 to permit the proper amount of cooling air to flow through the tubes 21 to effect proper cooling of the liquid during its flow through the casing 10, and from said housing 16 through the outlet opening 20.

In the event of a sudden acceleration of the speed of the engine such as might produce a surge of the liquid causing the heat exchange core portion of the unit to become choked, or in the

event of congelation of the liquid in the heat exchange core portion of the unit during a period of idleness of the engine, with consequent obstruction to flow of the liquid through said core portion, and upon subsequent starting of the engine, the pressure of the liquid in the system will rise and the valve 19 will open. Thereupon, the liquid will follow a path of flow, as indicated by the dotted lines in Fig. 2, from the inlet opening 12 through the passageway a in by-passing relationship to the heat exchange core portion of the unit contained in the casing 10, through the openings 15 and 18 into the housing 16, through said housing in by-passing relationship to the thermal element 25 due to the provision of the check valve 28, and from said housing through the outlet opening 20.

Assuming that the liquid in the heat exchange core portion of the unit has become congealed during a period of idleness of the engine, that the engine has been started, and that hot liquid is flowing through the passageway a in by-passing relationship to said heat exchange core portion, it is apparent that the heat of the by-passing liquid will act upon the congealed liquid in the outer or peripheral part of the core portion of the unit to de-congeal the same, whereupon flow will be resumed through said core portion and the de-congealing process will progress inwardly until all of the liquid in said core portion has been de-congealed. Heretofore, however, until the by-passing liquid has acted to de-congeal sufficient of the congealed liquid in the outer or peripheral part of the core portion of the unit to re-establish flow through said core portion, and even thereafter until sufficient time had elapsed for the shutters to open, the circulating portion of the liquid remained excessively hot because it was not subjected to any cooling action during its flow through the heat exchange unit. As distinguished from this, the present invention provides for flow of cooling air through the outer or peripheral part of the core portion of the unit at all times. Therefore, even when the hot liquid is flowing in by-passing relationship to the core portion of the unit through the passageway a, it is subjected to a certain amount of effective cooling which is increased as flow is resumed through the outer or peripheral part of said core portion prior to opening of the shutters. It is therefore apparent that the present invention provides for cooling of the intensely hot liquid during the critical time beginning with initiation of flow of the hot liquid in by-passing relationship to the core portion of the unit and lasting until flow through the core portion has been resumed and the shutters 24 have opened. Thereafter, of course, the cooling is regulated by shutters 24 as heretofore.

It further will be noted that by cooling the hot liquid in the peripheral portion of the core section, actuation of the thermostat 25 to open the shutters 24 is delayed. In this manner, the less readily decongealed central portion of the core section is protected from additional cooling until the decongealing process is complete or substantially so.

Without further description it is thought that the features and the advantages of the invention will be clearly understood and appreciated. It is desired to point out, however, that while only a single specific structural embodiment of the invention has been illustrated and described, the same is readily capable of embodiment in various specifically different structures within its

spirit and scope as defined in the appended claims.

I. claim:

1. A heat exchange unit for use in a closed-circuit viscous liquid circulating system to cool the liquid during its circulation through the system, said unit comprising a casing having an inlet and an outlet for the liquid, means at the peripheral portion and also at the center portion of said casing for flow of air therethrough in cooling relationship to the liquid flowing therethrough, means to cause the liquid normally to flow through said casing and to flow in bypassing relationship thereto over the outside thereof when the liquid therein is congealed, a shutter casing mounted upon said first mentioned casing at one end thereof and extending beyond said end thereof, said shutter casing including an inner end portion of substantially the same cross sectional size and shape as said first mentioned casing and an outer end portion of reduced cross sectional area, a wall connecting said inner and outer end portions of said shutter casing and having openings therein for flow of cooling air at all times through the air flow means at the peripheral portion of said first mentioned casing, shutters in the said outer end portion of said shutter casing for regulating flow of cooling air through the central portion of said first mentioned casing, and means operable in response to variations in the temperature of the liquid when it is flowing through said casing to effect air-flow-regulating actuation of said shutters.

2. A heat exchange unit for use in a closed-circuit viscous liquid circulating system to cool the liquid during its circulation through the system, said unit comprising a casing having an inlet and an outlet for the liquid, open-ended tubes extending longitudinally through the peripheral portion and also through the center portion of said casing for flow of air therethrough in cooling relationship to the liquid flowing therethrough, means defining a passageway extending around said casing exteriorly thereof through which the liquid flows to the inlet of said casing, means to cause the liquid normally to flow through said passageway and said casing and to flow in by-passing relationship to said casing through said passageway when the liquid in said casing is congealed, a shutter casing mounted upon said first mentioned casing at one end thereof and extending beyond said end thereof, said shutter casing including an inner end portion of substantially the same cross sectional size and shape as first mentioned casing and an outer

end portion of reduced cross sectional area, a wall connecting said inner and outer end portions of said shutter casing and having openings therein for flow of cooling air at all times through the tubes in the peripheral portion of said first mentioned casing, shutters in the said outer end portion of said shutter casing for regulating flow of cooling air through the tubes in the central portion of said first mentioned casing, and means operable in response to variations in the temperature of the liquid when it is flowing through said casing to effect air-flow-regulating actuation of said shutters.

3. An oil temperature regulator for use in engine lubrication systems, comprising a core section made up of a plurality of open ended tubes assembled for the passage of air therethrough as a coolant and for the passage of oil therearound to be cooled, said oil congealing around said tubes when excessively cooled, a casing surrounding said tube assembly and formed with openings defining the inlet and the outlet for the oil flowing to and from the core section, means for by-passing oil around said casing when said core section is congealed, said by-passing oil flowing in intimate contact with said casing and transmitting heat therethrough to decongeal relatively quickly the peripheral portion of said core section and gradually the central portion thereof, shutter means at one end of the regulator for controlling the flow of air through said core section, a thermostat responsive to the temperature of the oil leaving said core section for initiating operation of said shutters, said thermostat acting in response to a rising temperature to cause movement of said shutters toward open position, and means allowing a continuous flow of air through the peripheral portion of said core section irrespective of the position of said thermostat, whereby to cool the quickly decongealed oil in said peripheral portion and prevent opening of said shutters before substantial decongelation of the central portion of said section is obtained.

4. An oil temperature regulator according to claim 3, characterized in that said shutter means and said means for allowing a continuous flow of air are comprised in a casing extension having one end fitted to an end of said casing and having an opposite projecting end mounting shutters, said projecting end being of reduced diameter whereby said shutters cover only the central portion of the core section, and the intermediate area of said extension being formed with openings aligned with the peripheral portion of said core section.

WALTER H. GEDDES.
